SIGNATURE FEEDING

Paul Schweizer, Easton, Pa., assignor to T. W. &
C. E. Sheridan Company, New York, N. Y., a
corporation of New York

Application September 9, 1939, Serial No. 294,057

23 Claims. (CL 271—12)

This invention relates to signature feeding, the term "signature" being intended to include sheets or other components of pamphlets or like products. The invention has to do with the feeding of signatures in the sense of extracting them consecutively from a stack or stacks, for example, from each of a series of aligned stacks for the transfer of the successive extracted signatures to the place of gathering or other operation, such as printing, cutting, embossing or folding. In an important aspect the present invention pertains to the type of extraction of successive signatures from a stack wherein the signatures stand edge-wise and are extracted edgewise and preferably by an approximately vertical, that is, upward or downward, pulling movement from the front of the stack. An example of a signature feeding and gathering machine for such purposes is that illustrated in U. S. Patent No. 2,162,732, granted June 27, 1939 upon an application filed August 12, 1937 by this applicant and others. The present invention in one aspect may be considered an improvement upon said prior patent, some features of which have been partially embodied herein, but the present invention in a broad aspect is not intended to be limited to use in a machine containing the features characterizing said patent, since substantial features of improvement herein disclosed may be used otherwise to advantage.

A special utility hereof is to render more practical the operations in a gathering machine in which so-called lap signatures are stacked edge-wise and after extraction are successively opened and deposited upon a saddle, known as insert gathering, to which class said prior patent belongs.

A general object of the present improvement is to afford a feeding mechanism for signatures, and like components, which is capable of a high speed of operation and rate of output. A further object is to afford improved reliability of signature extraction and transfer from a stack, by ensuring the extraction of only a single signature in each operation and by positively ensuring its engagement by the means or device transferring it away to another operation. Other objects are to simplify the extraction of a signature from a stack of signatures standing edgewise, and to reduce the resistance and drag of such extraction, and to provide for separation of the respective actions of extraction and subsequent transfer or travel of the successive signatures. Another object is to facilitate the handling of relatively narrow signatures, such for example as the so-

called gangs, each consisting of a plurality of integrally united signatures adapted to be gathered into groups and subsequently severed into two or more products. An additional object is to facilitate the loading of the hopper which contains the stack. Further objects and advantages will be explained in the hereinafter following description of an illustrative embodiment of the invention or will be manifest to those conversant with the subject.

A special object is to perfect and expand the usefulness of insert gatherers, wherein lap signatures are stacked edgewise, transferred, opened, and deposited upon a group travelling along a saddle.

In the accompanying drawings, Fig. 1 is a general left elevation view of a signature feeding apparatus embodying the present invention, corresponding generally with Fig. 1 of said patent, with certain longitudinal parts and shafts shown in transverse vertical section, the front of the machine being considered to be at the right hand side of Fig. 1; a top plan view being considered unnecessary in view of the incorporation of such a view in said patent, which may be referred to for various matters of arrangement and construction not herein fully illustrated.

Fig. 2 is a diagrammatic view of certain parts shown in Fig. 1, but showing such parts in a different position or stage of operation.

Fig. 3 is a view similar to Fig. 2 but showing the same and other parts in another position or stage of operation.

The general parts of the machine include the lower frame 10 extending to the floor, and the upper frame 11 containing bearings and supports for various longitudinal shafts and parts. At the upper rear is shown the loading shelf 12 located conveniently to support supplies of signatures in preparation for their rear loading into each of the respective hoppers of the series, of which there may be a considerable number in accordance with usual gathering practice. Various other brackets or extensions of the frame are provided for various purposes, among which is indicated an upper front bracket 13 carrying a frame bar 14 and supporting certain of the transfer and delivery mechanisms. For convenience the machine is shown as delivering opened signatures on to a saddle, as in said patent, and a traveling saddle mechanism 15 is shown, which may be conventional. Many of these general parts are indicated only in dot-and-dash outline.

A stack S is shown consisting of individual signatures standing edgewise as in said patent, in

distinction to being stacked flatwise as is frequently done. Although the signatures in each hopper rest upon their lower edges they do not stand exactly vertically but stand tilted over 5 frontwardly to a substantial angle, in this case about 30° from the vertical as compared with 15° in said patent. This arrangement is found to facilitate the loading of signature supplies in each hopper, each batch more readily assuming and 10 holding its stacked position, in which the bulk of the signatures may be bowed as in said patent.

The several hoppers supply in each cycle the different signatures required to constitute each pamphlet or other product, and the feeding and 15 transferring mechanisms hereof operate to extract in an orderly manner the respective signatures and deliver them regularly, in this case upon the traveling saddle 15, so as gradually to build up signature groups G as indicated.

20 Journalled in the machine frame is shown the main shaft X running the entire length of the machine, making one revolution per cycle, and serving in coordination the various hoppers, feeding mechanisms and transfer mechanisms. Carried on the main shaft are a number of operating cams x^1 , x^2 , x^3 etc., the connections from which to the various parts of the mechanism are illustrated and will be hereinafter described.

25 Referring next to the signature hopper or stack holder, the drawings show the hopper as comprising a lower side plate 18 at each side and an upper side plate 19 at each side, these being mounted upon a base or carriage 20 which may be supported on rear and front rods or axles 21 and 22. The hopper bottom may comprise one or a pair of feed belts 24 supporting the stack. Each belt is shown passing around rear and front belt pulleys 25, the front one of which may be driven slowly by ratchet mechanism 26 to 26° analogous 30 to that shown in said prior patent and similarly controlled, therefore needless to describe.

35 By these arrangements, the signatures are stacked edgewise as shown, preferably with their back edges down, so that each signature may be later opened centrally for deposit on the saddle 15. The signatures may be bowed rearwardly for greater stability in the stack, as in said patent. This is not always essential, but in the case of 40 long and narrow signatures or gangs this bowing is useful for a special reason. The bowing is produced by the spacing of the side plates 19 slightly closer together than the horizontal 45 length of the signature. These plates terminate short of the front of the stack, as in said patent, 50 so that a few of the signatures at the front are released from the bowed condition. The bowing of the bulk of the signatures reduces the extent of frontward pressure on the front signature and this materially eases the friction thereon during 55 each extracting operation.

60 There is also shown a small roller or feeler 27 at the lower front part of the hopper, constituting a stop restraining the lower edges of the frontmost signatures from swinging frontward in an uncontrolled manner, while permitting the 65 extreme or front signature to be released therefrom when pulled frontwardly thereover.

65 Each hopper is completed by the provision of a front abutment or wall 29, of less area than the 70 signatures, against which the middle part of each of the front signatures of the stack bears until extracted. The abutment is mounted on a support 30 carried on the bar 14 and so may be of less dimension than the front signature both 75 horizontally and up and down; or there may be

one long front wall 29 for the entire series of hoppers.

The balance of the description of the disclosed apparatus will be in substantially the following order. The detaching means will first be described, comprising a suction detacher 35 acting near one of the horizontal edges of the first or front signature to detach or swing it sufficiently away frontwardly from the next signature to permit the subsequent operations. The detaching 10 action is shown performed at the bottom edge of the front signature, since the preferred operation is to extract each signature downwardly to a stopped position and then reverse its travel into an upward direction commencing the transfer 15 away to the subsequent operations; but this plan might be reversed on the same principles by detaching the top edge of the signature, extracting it upwardly to a stopped position and then transferring it away with downward travel. In either 20 case the detacher preferably works at the back or folded edge in the case of a signature, that being the only edge of the ordinary signature that is capable of bodily detachment by suction. This is especially true of a lap signature characterized 25 in that a half of it is wider than the balance, forming a lap, for later opening.

The next branch of description deals with what is herein termed a separator 45, which is an instrument that enters between the edge of the detached signature and those behind, isolating the detached signature at such edge and then repressing or forcing back the stack behind the front signature, this separator later performing an additional positioning function auxiliary to 30 the transfer movement.

35 Next shall be described the extracting means 60, of gripper type, shown as operating in a downward direction, pulling the front signature wholly out of the stack and bringing it to rest in a lowered position with its top edge free. Finally will be described the transfer means, shown as a drum and gripper device, to engage the free or top edge of the extracted front signature, and pull it out or up and thus away to where the signature 40 may be disposed of, for example by opening and delivering it upon a saddle.

45 The detacher 35 is shown in the usual form of a suction cup on a hollow arm, these being mounted on a hollow carrier 36 which is swingable and has a suitable pneumatic connection, not shown. The several carriers 36 are mounted on a common rockshaft 37 by which all of the 50 detachers may be swung in unison.

55 The detacher 35 may have the usual detaching action, similar to that shown in said patent, by swinging rearwardly to a first or signature engaging position, and then retracting frontwardly to swing the signature edge out away from the stack. As usual there may be two or more 60 suction detachers for each stack, engaging each front signature near its lower closed edge, thereby to swing such edge out, free from the feeler or guard 27 and from the remainder of the stack. The detacher may thus bring the signature edge 65 to a suitable extracting position, which is preferably the natural position of the signature, as shown, in alignment with the front abutment plate 29. See Fig. 3.

70 There is disclosed a special detaching operation, which may be optional, consisting in causing the detacher 35 first to swing outwardly or frontwardly too an extra extent, beyond the natural or straight position of the signature, so as to flex it frontwardly, to the position shown 75

in Fig. 2. This excess frontward swing of the signature lower edge assists in stripping from it the next succeeding signature in case the two should tend to adhere through pneumatic, electric or other action. When the front signature is thus swung to its extreme front position, as shown in Fig. 2, the next succeeding signature, if it has been accidentally swung frontwardly with the first one, is thus released and swings back to the middle position shown in dotted lines in Fig. 2. This gives a positive assurance of a substantial gap behind the front signature edge, thus reliably to admit the separator member to be described. This special swinging action insures the provision of an ample space for the reception of the separator.

The detacher then preferably swings back partway toward initial position, easing the front signature to its intermediate or extracting position, in straight line with the balance of the signature, it being understood that the separator has in the meanwhile entered between the first and second signatures, isolating the former. A similar result might be obtained if the suction device 36 should release the front signature, to return naturally to its extracting position, after the separator has entered behind it. In either case the front signature reaches the proper position to be gripped and pulled down, remaining there until the extracting operation, to be described.

The third or return motion of the detacher takes place after it has released the front signature, and such signature has been drawn down and out of the stack, the detacher then swinging back to the stack to engage the next succeeding signature while the previous one is being transferred away for delivery. While these several actions have been described with reference to the lower edge of the signature and its downward extraction, the operations are invertible and might take effect in a similar manner at the upper or top edge of the signature, although to much less advantage.

Suitable timed operating connections for giving the detacher its double operation between three positions are indicated. The rockshaft 37 carrying the suction devices is provided at a convenient point with a rockarm 38 extending rearwardly and connected by a depending link 39 with the extremity of a lever arm 40 turning loosely upon a fulcrum rod or axle 41, said lever arm being united with a lower arm 42 carrying a follower 43 running upon the cam surface or periphery of a cam x^1 mounted on the main shaft X. The cam x^1 being shown as an open cam suitable spring means will be understood to be operating upon the train 31-42 to hold the follower 43 in contact upon the cam.

The contour of the cam x^1 is such as to give the described double action between three positions. Fig. 2 shows the follower on the high point of the cam, and the detacher at its extreme front position. After a dwell, further clockwise rotation brings the next dwell of the cam to the follower, adjusting the detacher to its middle position, during which dwell the extractor engages the signature and the suction is relieved. Further rotation brings the lowest part of the cam periphery to the follower, causing the detacher to swing back, engage the next signature and quickly start frontwardly again, subsequently, of course, to the extraction of the previous signature.

The next main element or instrument is the

separator 45 shown in the form of a finger or hook. This member is a separator in any one or more of three senses in that it first isolates the front signature from those behind and second represses those behind, including the stack, 5 to aid extraction, and third acts on the isolated front signature top edge to position it away from the stack to aid transfer. The connections will first be described and the actions then recited in further detail.

The separator 45 is mounted at the front end of a carrier 46 shown in the form of a bar, the rear end of which is pivoted to the top end of a rockarm 47 mounted on a rockshaft 48. There being two or more of the separators for each 15 stack, the rocking of the shaft 48 performs the movements for the separators for all of the stacks.

When the separator 45 moves frontwardly and rearwardly it has certain up and down movements which may be effected by a stationary cam. For this purpose the separator carries a follower or roller 49, and this rolls along the accurately designed surface of a fixed cam 50, the upper portion of which is substantially straight 25 and parallel to the floor of the hopper, while the front edge 51 is relatively inclined, as best shown in Fig. 2, so that when the separator moves rearwardly from the Fig. 1 position the follower first rides up on the incline 51 to the Fig. 3 position and then along rearwardly to the Fig. 2 30 position. The cam edge 51 is steep so that the finger rises quickly as it shifts rearwardly, clearing the edge of the front-swung signature and safely entering the space directly behind it; 35 thereupon thrusting back upon and relieving the pressure of the stack.

To bring about these movements the rockshaft 48 is provided with a rockarm 53 which is connected to a depending link 54, the lower end of 40 which is connected to a lever arm 55 swinging loosely on the rod or axle 41. Beyond the axle the lever hub carries a second or lower arm 56 at the extremity of which is a follower 57 bearing on the contour of a cam x^2 on the cam shaft 45 X; spring means being assumed to hold the follower to the cam.

The three functions of the separator are described as follows, the contour of the cams x^2 and 50 50 being such as to afford the necessary movements. The first action may be understood by comparing Figs. 1 and 3. The follower 49 slides up the incline 51, causing the separator to rise from its low front position as it moves rearward, this rise occurring while the front signature is still held swung full frontward as in Fig. 2, so that the separator finger rises behind the front signature, between it and the stack, and in front of any signatures which accidentally have been drawn away from the stack. This 60 position is shown dotted in Fig. 2. The separator has thus far performed its isolating function, leaving only the front signature in front of it. The separator itself is omitted from Fig. 3 in order to show more clearly the parts beyond. 65 Indeed, in Fig. 3, the parts are actually on their frontward return movement.

The next separating action is the most essential, consisting in repressing the stack, including all signatures behind the front one, affording a 70 thrusting or lifting action, pressing the weight of the stack away from the abutment plate 28, at the two sides, and thus relaxing the pressure of the stack thereon and materially relieving the friction otherwise acting on the front signature. 75

Fig. 2 fully shows this repressing action, which takes place just before the downward extraction, materially aiding the extracting action.

The third or supplemental function of the separator 45 is to act upon the top edge of each extracted signature, after it has been pulled down out of the stack, to separate such upper edge in the sense of positioning it frontwardly, in a reliable manner, to cooperate with the gripping or other transfer engagement upon such upper edge, for transporting the signature away to a remote point of delivery. Fig. 1 shows the separator performing this function, its frontward shifting movement operating to deflect the signature top edge into the path of the transfer gripper. The action expedites and positively insures the correct positioning of the signature, which otherwise, especially with light signatures and high speed of operation, might fail to arrive at the transfer position in time for gripping and removal. This positive mechanical function dispenses with a pneumatic positioning action by means of air puffs, which would be less reliable and more difficult to provide.

Various adjustments between separator 45 and cam x^2 may be provided, e. g. the length of link 54 for initial setting, or its point of pivoting to arm 53 to change the throw of the separator.

Coming next to the extraction of each front signature, this is shown performed by a reciprocating extractor 60, consisting of two pairs of gripping jaws, one near each side, each jaw-pair comprising a relatively fixed jaw 61 and a swinging jaw 62. These grippers are arranged and operated to grip the front signature at two opposite points and pull it down completely out of the stack while the weight of the stack is relieved by the separator 45. Each gripper reciprocates or swings bodily, rising to a position to engage the closed bottom edge of the front signature when it stands in its natural or extracting position determined by the detacher, as shown in Fig. 3, the gripper lowering movement being in alignment with such intermediate or natural position of the signature. The lowering of the extractor wholly removes the signature from the stack and brings it to rest in a precise stopped position, predetermined by adjustment, so that the signature top edge will move down to an exact point lower than the stack, becoming free for accurate engagement by the transfer means. By this order of steps the transfer is relieved from the burden of extraction, and the transfer is initiated without any substantial drag upon the signature. This plan further permits the handling of narrower or smaller signatures because there is no necessity of top edge separation and extraction as illustrated in said prior patent.

The extracting gripper 60 is mounted at the free end of a carrier lever 63 which is a long lever swinging from a high rear axis and bent for clearance purposes. Its effective length when raised is approximately parallel to the hopper bottom. The lever 63 is fast on a rockshaft 64 and to the same rockshaft is attached a second rock lever or arm 65 formed with a slot 66 for adjustment purposes. A pivot stud 67 may be set to different positions in the slot 66, and the stud is connected by a long link 68 with the free end of a lever arm 69, which constitutes a cam lever fulcrumed below at 70 and carrying a follower or roll 71 running upon the contour of a cam x^3 on the main shaft X. To hold the follower resiliently to the cam there is shown a

third rockarm 73 on the rockshaft 64, and from the free end of this rockarm extends a rod 74 sliding in a fixed bracket 75, with a spring 76 confined between said bracket and a head 77 on the rod. The spring therefore, under strong compression, swings the rockarm 65 in a manner to hold the follower 71 to its cam, and to retract downwardly the gripper 60, affording a cushioning yield.

The adjustment of the stud 67 in the slot 66 determines the extent of swing or stroke of the carrier lever 63 and therefore the point to which each signature is lowered in the extracting movement. The gripper however should always rise to exactly the same signature engaging position. The curvature of slot 66 therefore is such that, when the lever 63 and gripper are raised the arc of the slot is concentric to the pivot between lever 69 and link 68 about which pivot the link swings during the adjustment of the stud 67 in the slot. The adjustment therefore changes only the stroke-length and the bottom limit of gripper swing, which has to be varied with the vertical width of the signatures.

It is important that the top open edge of the signatures shall be presented at an exact predetermined point or height to the transfer drum grippers, and the described arc adjustment 66, 67 of the downward extracting stroke provides the means for this. The gripper always starts down from the same level, and when lowered brings the signature top edge always to the same level, whatever its width. The gripper oscillating cam x^3 is seen to have a substantial dwell at the lowered gripper position. While at this dwell the signature rests stationarily in proper register for its top edge to be gripped by the transfer drum grippers. This gripper pause constitutes a stop for the lowered position of the extracted signature, and permits the grippers to be opened, releasing the signature, before the transferring grippers grip and pull it up and away. The cam dwell also is so prolonged that when the gripper later swings up for the next extraction it can not overtake the signature being transferred. This sequence of gripper lowering, releasing and delayed rising actions is possible by the use of a timed cam x^3 , whereas a simple crank motion would not serve.

The grippers 60 must each be opened and closed in proper time with its shifting movements, the gripper rising in open condition, closing upon the signature edge, lowering in closed condition to extract the signature, and finally opening in its adjusted lowered position to release the signature. To perform these movements the gripper jaw 62 has a tail or extension 80 shown connected by a link 81 and pivot 82 with a rock-arm 83 carried on a rockshaft 84. The pivot 82 is a floating pivot, with a universal joint, and with adjustable cushioning springs preventing positive jaw closing movements which might be injurious to the material. By rocking the shaft 84 the jaws are opened or closed, and for this action there is shown a rockarm 85 attached to the shaft and connected by a depending link 86 with a lever 87 swinging loosely on the axle 41. On the same hub with the arm 87 is a second arm or cam lever 88 carrying a follower 89 engaged upon the cam x^4 on the main shaft X, the cam having the proper contour to cause the gripper jaw movements as described. The rockshaft 84 is preferably located close to the rockshaft 64 instead of having them concentric, which would be theoretically preferable but difficult in con-

struction. The shaft 84, with its arms 83 and 85, is hung from the shaft 64, so that these all partake of the swinging of rockarms 63 and 65; and the gripper opening cam 24 is designed for correct timing with these factors in consideration.

To guide and render uniform the lowering movement of each signature there is shown a pair of opposite signature confining rollers 94 mounted upon adjustable arms 95 and so positioned as to press and hold frontwardly each descending signature, for example, against an inclined receiving plate or wall 96 shown mounted on a bracket 97 fixed on a rod 98, by clamping means affording adjustment. This plate or signature support is an important element for the reason that the extraction movement ceases and the grippers 60 open substantially before the drum grippers close upon the signature. The released signature while pausing rests against the plate 96. Between the guide rollers 94 and the signature rest 96 is a gap through which the lower part of the signature is pulled down.

Below the guide roll 94 the rest plate 96 may be continued as shown, in curved shape approximating the path of the descending grippers. Its lower part 99 may also be grooved, as shown, at its opposite sides, or elsewhere not conflicting with the extraction. The grooved edges of the plate compel the descending signature to assume the curved form of the plate between the grippers and the guide roll. Without this provision signatures might in some cases assume the curve but in other cases straighten out below the guide rolls and thus cause decided variations in the level of the signature top edges, especially with vertically wide signatures. The described arrangement thus gives assurance that every extracted signature, wide or narrow, will come to rest with its top edge accurately positioned for engagement by the transfer grippers.

The receiving support or rest 96 thus advantageously cooperates not only in the extracting but in the transferring operations. The plate extends above the rolls 94 at an upward forward incline with its uppermost edge adjacent to the transfer device or drum 106. The extractor is carefully adjusted for each size of signature, as described, so that the signature will be lowered until its top edge comes to an exact point, which may be at or slightly above the top edge of the plate 96. By this arrangement the signature extreme top may even rest upon the periphery of the transfer drum, the most suitable position for reliable gripping and transfer.

While the pausing lowered grippers 60 constitute a stop, as explained, for the lowered position of each extracted signature, a finer accuracy may be provided by a supplemental means to ensure correct transfer, such as a sheet forwarding device comprising an opposite pair of rollers, per se well known, pressed together in light feeding contact and continuously running; so that by opening the retracting grippers 60 after full extraction and after the signature has engaged between the feed rollers, the signature, freed from the grippers, is kept moving downward a short distance until meeting an accurately positioned fixed stop, at which the rollers hold it yieldingly until the transfer grippers pull it up and away.

When each edgewise extracted signature has come to a pause as described with its top edge at rest against or adjacent to the transfer drum 106 it is ready to be gripped at its top edge and pulled out or upward and away by means of

transfer grippers 105, of which there may be one or two or more sets, at evenly spaced points on the periphery of the drum, two sets being indicated. The separator 45 cooperates in this action by reason of its forward shift, as shown in Fig. 1, ensuring that the top edge of the signature has been shifted or settled accurately into its transferring position.

The transfer drum 106 and its gripper system may be substantially as in said prior patent, 10 wherefore they are not described in detail. The drum is preferably of skeleton form, composed of several disks or wheels, and is shown as having a diameter sufficiently large to provide a gripper set at each of two opposite points. The 15 details of the grippers and their mode of action may be ascertained by reference to said patent.

The transfer drum 106 is carried on a shaft 107 which is rotated by means of a sprocket gear 108 on the shaft connected by a sprocket chain 20 109 with a sprocket gear 110 on the main shaft X, the chain passing also over an idler 111 on arm 112. The gear 108 is shown twice the diameter of the gear 110, so that in each cycle or rotation of the shaft X the drum will make 25 only a half rotation, due to the fact that there are two gripper sets spaced 180° on the drum. The drum turns continuously and each gripper, as it comes to gripping position, is swung rapidly in a manner to press and grip the signature 30 against the periphery of the drum. A gripper set may comprise two or more grippers along the length of the drum and these readily engage and pull upwardly the successive signatures, which are thus carried around with the drum to delivery position. The receiving wall 96 may be of open construction and recessed where the grippers 105 operate against the drum, or even cut away to avoid any contact with the peripheral parts of the skeleton drum.

Without going into details, but with reference back to said patent, the illustrated delivery means may be described as comprising, in this case, a signature-opening cylinder 115, which may be half the diameter of the transfer drum 45 and of a similar skeleton construction. The cylinder is mounted on a shaft 116 at the same level with shaft 107. For driving the opening cylinder its shaft is provided with a gear 117 co-operating with a gear 118 on the drum shaft, 50 the latter gear being of twice the diameter of the former. Beyond the cylinder 115 is shown an idler gear 119, and there is another idler gear 120 at a higher level. The drive of the cylinder is effected by a sprocket chain 121 passing around the drum gear 118, the idlers 120 and 119 and the cylinder gear 116, giving the latter one rotation for each half rotation of the drum, that is, for each signature extracted from the stack and transferred.

During the transfer of each signature from the stack around to the delivery it may be held snugly upon the transfer drum by means of endless tapes 123 each of which runs upon the drum and upon the opening-cylinder and upon 65 an idler pulley, similarly to the corresponding elements in said patent.

Suitable means is to be understood for opening each transferred signature and delivering it in opened condition upon the saddle 15. This opening means may consist of devices provided partly on the drum 106 and partly on the cylinder 115, acting to open up widely the advance edge of each signature and thrust it downward astride the saddle.

The operation on each of the successive signatures from stack to delivery may be as follows, with reference to Figs. 1, 2 and 3, Fig. 2 showing the main shaft and cams 180° beyond Fig. 1 and

- 5 Fig. 3 90° therebeyond. The front signature *s*, formerly bowed by walls 19, now stands edgewise flattened against the abutment 29 standing at a frontward tilt; while its back or extracting edge is restrained by the stop roller 27. Assuming 10 downward extraction, the detacher 35 swings toward the signature lower edge, Fig. 1 showing it in such movement; and it engages the lower edge, and by suction swings it past the stop 27 and frontward, far beyond its natural or extracting position. Fig. 2 shows this position, the edge being bent around the edge of abutment 29 thus shedding any clinging signatures.

Now the separator 45 enters, by rising obliquely, to clear the signature edge and come in behind it, isolating it. The separator thence moves 20 forcibly rearward, restoring any loose signatures to the stack and repressing the latter to relieve the drag on the isolated front signature. The detacher now causes the front signature to swing 25 to its intermediate or aligned position, as in Fig. 3, ready for extraction.

The extractor 60 meanwhile has risen, its open 30 jaws engage the signature edge, the jaws close and the extractor pulls the signature edgewise downward and out, its pulled edge passing between roll 94 and receiving plate 96. At a predetermined point the descent ceases and the signature is stopped, with its top edge approximately at the transfer point, the separator now shifting frontward as in Fig. 1 to deflect and 35 position the top edge against the transfer drum 106.

The drum grippers now engage the last 40 emerged or top edge of the signature and draw it edgewise out or up and away; so that there is a change or reversal of signature travel direction between extraction and transfer. In the meanwhile, as the transfer begins, the detachment and extraction of the next signature commence, so that there is no loss of time and the feed is in rapid succession.

As already set forth the directions of motion 45 may be different. The edgewise extraction may be upward or even lateral, so long as it completely removes the signature from the stack and stops at a predetermined point, and the transfer is next performed edgewise by a different edge, preferably the opposite or last-emerged edge of the extracted signature. When so extracted 50 laterally and transferred in an opposite direction after a pause the transfer and accumulation of signature groups may be in accordance with patent of Krueger No. 2,173,118 issued September 19, 1939.

60 The present invention permits a gatherer to operate on signatures of varying vertical width, from 12 inches or more to 5 inches or less, and of varying horizontal length from 10 inches or less to 25 inches or more in the case of gang work. This capability does not exist with the gatherer of prior patent 2,163,732, which can not handle signatures of low width or excess length because of the requirement of a preliminary partial downward retraction, behind the abutment plate, leaving insufficient or no top margin for deflection and transfer gripping.

I claim:

1. Mechanism for feeding stacked signatures or sheets one by one from a hopper wherein 75 they stand edgewise upon a hopper bottom and

bear against a hopper front abutment or wall and presenting them to a transferring device or drum with grippers, comprising, a detacher constructed and operated to engage the folded edge of each front signature to be fed and swing it 5 frontwardly from the stack to extracting position, a separator constructed and operated to enter behind such detached signature and between it and the succeeding signatures and thereupon to repress the succeeding signatures 10 back towards the stack, and an extracting gripper constructed and operated to grip the detached edge of the front signature while the separator presses backwardly the succeeding ones, and to pull out and completely extract the 15 front signature and bring it to a stop with its last emerged edge in a definite position for such transfer gripping.

2. Mechanism for feeding stacked signatures or sheets one by one from a hopper wherein they 20 stand edgewise upon a hopper bottom and bear against a hopper front abutment or wall and presenting them to a transferring device or drum with grippers, comprising, a detacher constructed and operated to engage the lower edge of each 25 front signature to be fed and swing it frontwardly from the stack beyond extracting position to shed any clinging signatures, and later back to extracting position, a separator constructed and operated to enter from below behind such 30 detached front signature to isolate it from the succeeding signatures and thereupon to repress the succeeding signatures back toward the stack, and an extracting gripper constructed and operated 35 to grip the lower edge of the detached front signature while the separator holds back the succeeding ones, and to pull downward and completely extract the front signature and bring it to a stop with its free upper edge in a definite 40 position for such transfer gripping.

3. Mechanism as in claim 2 and wherein the separator, after extraction, shifts frontwardly to deflect the upper edge of the extracted signature toward the drum into position for transfer gripping.

4. Mechanism for feeding stacked signatures or sheets one by one from a hopper wherein they stand edgewise upon a hopper bottom and bear against a hopper front abutment or wall and presenting them to a transferring device, comprising, a suction detacher constructed and operated to engage the lower edge of each front signature to be fed and swing it frontwardly from the stack to extracting position, a separator constructed and operated to enter from below behind such 50 detached front signature and between it and the succeeding signatures and thereupon to repress the succeeding signatures back toward the stack, and later to deflect the upper edge of the extracted signature frontwardly towards the drum in position for transfer gripping, and an extracting gripper constructed and operated to grip the lower edge of the detached front signature while the separator holds back the succeeding ones, and to pull downward and completely extract the front signature and bring it to a stop with its free upper edge in a definite position for such frontward deflection and transfer gripping.

5. Mechanism as in claim 4 and wherein is a 70 receiving plate against which the lowered signature may rest with its upper edge free in position for transfer gripping and wherein the deflecting action of the separator thrusts such upper edge toward said plate.

6. Mechanism as in claim 2 and wherein the hopper has a restraining guard holding back the lower edge of the front signature behind its extracting position until detached and wherein the extractor operates by reciprocation along a path in line with the front abutment.

7. Mechanism as in claim 1 and wherein the extractor is mounted to reciprocate between the stack and a predetermined lowered position whereat the signature is stopped between extraction and transfer.

8. An insert gathering machine comprising signature hoppers adapted to contain signatures standing edgewise with their closed back edges down, each hopper having a front abutment wall against which in turn each front signature bears, a detacher operable to engage the signature bottom edge and swing it frontwardly to extracting position, a separator operable to rise behind the detached signature and repress the succeeding signatures and stack, an extractor comprising grippers and operable to grip the detached edge of the signature and draw it downwardly and completely out of the hopper and bring it to a pause and release it with its top edge in a definite position, and a transfer device or drum having grippers and operable to grip the positioned top edge of the pausing signature and transfer it upwardly and away for opening and depositing upon a saddle.

9. A gathering machine as in claim 8 and wherein the separator operating means causes it to shift frontwardly and deflect or position each pausing signature in a front position for gripping by said transfer device.

10. A gathering machine as in claim 8 and wherein is a cam for causing the extractor downward and return movements, said cam shaped or timed to cause the extractor to pause at its lowered position until the released signature has been gripped by the transfer drum and started on its upward transfer motion.

11. A gathering machine as in claim 8 and wherein is means for adjusting the length of stroke of the extractor between a constant gripper engaging position and a variable lowered position, in accordance with the vertical width of the signature.

12. A gathering machine as in claim 8 and wherein the extractor is carried on a lever for down and up swinging movements between signature gripping and stopping positions, with cam connections including a link pivoted to a rockarm for swinging said lever; and said pivot being adjustable on said rockarm along an arc, to change the stroke of the extractor; and said arc being concentric, when the extractor is at gripping position, with the adjusting swing of said link thereon; whereby the adjustment of extraction stroke to suit the signature width is readily effected without varying the signature gripping position thereof.

13. An insert gathering machine comprising signature hoppers adapted to contain signatures standing edgewise with their closed back edges down, each hopper having a front abutment wall against which in turn each front signature bears, a detacher operable to engage the signature bottom edge and swing it frontwardly to extracting position, a separator operable to rise behind the detached signature and repress the succeeding signatures and stack, an extractor comprising grippers and operable to grip the detached edge of the signature and draw it down-

wardly and completely out of the hopper and bring it to a pause and release it with its top edge in a definite position, a signature rest or plate against the rear side of which each extracted signature may rest when released, said 5 plate located to position the signature top edge for transfer gripping, and a transfer device or drum having grippers and operable to grip the positioned top edge of the pausing signature resting on said plate and transfer it upwardly 10 and away for opening and depositing upon a saddle.

14. A gathering machine as in claim 13 and wherein is a guide roll near the rear side of the signature rest plate between which and the 15 plate each signature is pulled down by the extractor.

15. A gathering machine as in claim 13 and wherein is a guide roll near the rear side of the signature rest plate between which and the plate 20 each signature is pulled down by the extractor; and the plate being extended below such guide roll in a curved shape approximating the swinging path of the descending extractor, thereby to receive and support the resting signature in a 25 curved position.

16. A gathering machine as in claim 13 and wherein is a guide roll near the rear side of the signature rest plate between which and the plate each signature is pulled down by the extractor; 30 and the plate being extended below such guide roll in a curved shape approximating the swinging path of the descending extractor, thereby to receive and support the resting signature in a curved position; such curved part of the plate 35 having signature grooves or guides compelling the signature to assume such curve, thereby to assure uniform positioning and register of all signature top edges for transfer gripping.

17. A signature gathering machine of the kind 40 having a series of hoppers from which successive signatures are extracted and transferred for grouping upon a gathering conveyor, the same comprising a detacher operable to swing an edge of each signature away from the stack to extracting position, an extractor having a gripper operable to grip the detached edge and pull the signature edgewise completely out of the stack and release it to stop with its last emerged edge in a predetermined position for transfer, a signature rest for supporting the extracted signature awaiting transfer, and a transfer device having a gripper to grip such last emerged edge of the signature on said rest and transfer the signature away for deposit on the gathering conveyor.

18. A machine as in claim 17 and wherein is a separator operable to enter behind each detached signature edge and after extraction to deflect the opposite edge to transfer position 60 on said rest.

19. A signature gathering machine of the kind having a series of hoppers from which successive signatures are extracted and transferred for grouping upon a gathering conveyor, the 65 same comprising an abutment wall against which the front signature bears, a detacher operable to swing the lower edge of each signature away from the stack to extracting position, a reciprocable extractor having a gripper operable to grip the detached edge and pull the signature downwardly completely out of the stack and release it to stop with its last emerged edge in a predetermined position for transfer, an inclined rest for supporting the extracted signature.

ture awaiting transfer, and a transfer device having a gripper to grip such last emerged edge of the signature on said rest and transfer the signature away for deposit on the gathering conveyor.

5 20. A machine as in claim 19 and wherein is a separator operable to enter behind each detached signature and repress the succeeding signatures, and after extraction to deflect the 10 signature forward to the rest.

10 21. A signature gathering machine of the kind having a series of hoppers from which successive signatures are extracted and transferred for opening and grouping upon a gathering saddle, the same comprising a detacher operable to swing the closed back edge of each signature away from the stack to extracting position, an extractor having a gripper operable to grip the detached closed edge and pull the signature 15 edgewise completely out of the stack and release it to stop with its open edge in a predetermined position for transfer, a signature rest for supporting the extracted signature awaiting transfer, and a transfer device having a gripper to grip the open edge of the signature on 20 said rest and transfer the signature away for opening and deposit on the gathering saddle.

25 22. A signature insert gathering machine of the kind having a series of stack hoppers from which successive signatures are extracted and transferred for opening and grouping upon a gathering saddle, the same comprising an extractor device having a gripper operable to grip each signature by its closed back edge and pull 30 it completely out of the stack and release it to

stop with its last emerged or open edge in a predetermined position for transfer, means for supporting the extracted signature while pausing for transfer with its open edge accessible for engagement, a transfer drum having a gripper to engage such last emerged open edge of the signature on said supporting means and transfer the signature away for discharge upon the gathering saddle, and an opening device or cylinder having a gripper to grip the outer half of 10 the signature on said drum and draw it away from the inner half during discharge.

23. A signature insert gathering machine of the kind having a series of stack hoppers from which successive signatures are extracted and 15 transferred for opening and grouping upon a gathering saddle, the same comprising an extractor device having a gripper operable to grip each signature by its closed back edge and pull 20 it completely out of the stack and release it to pause between extraction and transfer, means for adjustably predetermining the pausing position of each signature as to its closed edge according to its width so that its last emerged or open 25 edge will rest in a predetermined position for transfer, a continuously rotatable transfer drum having a gripper to grip such last emerged edge of the pausing signature and transfer the signature away for discharge upon the gathering saddle, and an opening device having a gripper to grip the outer half of the signature on said drum and draw it away from the inner half during discharge.

PAUL SCHWEIZER. 35
